CLAIM

The ornamental design for an electronic device, as shown and described.

DESCRIPTION

This application is related to U.S. application Ser. No. 29/664,867, filed Sep. 28, 2018, the entire disclosure of which is hereby incorporated herein by reference.

FIG. 1 is a front perspective view of an electronic device showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a rear perspective view thereof.

The broken lines in FIGS. 1-8 show portions of the electronic device that form no part of the claimed design.
